LOCK WITH PIVOTED TUMBLERS

Carl J. N. Hagstrom, Glen Head, N. Y.

Application December 22, 1948, Serial No. 66,689

15 Claims. (Cl. 70—353)

1

The invention relates to a lock adapted to be operated by a key. The lock is designed primarily to operate a switch, the switch being thrown by either right or left hand turning of the key. The lock, however, may be used as any lock to throw a bolt and the like; that is, the lock has general applicability. The lock is constructed particularly to operate upon both right and left hand rotation of the key and with lack of symmetry in the key as will appear more fully hereinafter. The lock may be constructed to operate in one direction only, if desired.

Some switches are thrown to closed and opened position by a $\frac{1}{8}$ revolution or pivotal movement of its operating member whereas other switches require a greater pivotal movement such as a $\frac{1}{4}$ turn. This necessitates at least an equivalent extent of rotation by the key and the operating hub of the lock. The lock is constructed so that the tumblers or leaves of the lock itself are suitable for use of the lock with either type of switch, thereby reducing the number of parts which must be manufactured and carried in stock to adapt the lock for use with either type of switch.

It is an object of the invention to construct a lock for right and left hand rotation of the key in order to operate the same with a key which may or may not have symmetry on the opposite faces thereof.

Another object of the invention is to construct a new and novel lock utilizing pivoted tumblers or leaves.

A further object of the invention is to construct a lock in which the tumbler or leaves are suitable for a lock to be operated through $\frac{1}{8}$ turn or $\frac{1}{4}$ turn of the key and operating hub of the lock.

A still further object is to construct a new and novel lock using a pivotally movable hub and locking post and a circular gate in the tumblers.

Another object is to construct a simplified lock in which the pivot for the tumblers serves also as a stop and may also serve as the anchor for a centering spring for the hub.

Another object is to construct a non-pick lock.

Other objects of the invention will be more apparent from the following description when taken in connection with the accompanying drawing illustrating a preferred embodiment thereof in which:

Figure 1 is a plan view of the lock with the cover plate removed;

Figure 2 is a plan view of the lock with the tumblers or leaves removed showing the hub of the lock.

2

Figure 3 is a plan view of the $\frac{1}{8}$ turn lock with the cover removed and the key turned therein to operated position to the left and with two of the tumblers removed on the right to show the third tumbler upon this side of the lock.

Figure 4 is a section through the lock taken on line 4—4 of Figure 1;

Figure 5 is a partial plan view of the lock with the hub turned to non-pick position.

Figure 6 is a plan view of the middle or second leaf or tumbler;

Figure 7 is an end view of a non-symmetrical key for operating the lock; and

Figure 8 is a plan view of the key of Figure 7.

The lock includes a frame or casing 10 which may take any form, that particularly illustrated being circular. A cover or cover plate 11 may close the open face of the casing or frame which is attached thereto in any fashion such as by screws

12. The casing has a hole 13 through the back face thereof for connection of the lock with a switch or bolt (not shown). A switch to be operated by the lock may be secured to the casing such as by screws 14. The cover or cover plate also has a hole 15 therethrough as well as a key slot 16.

Within the casing or frame is an operating hub 19 in the form of a semicircumferential plate mounted for rotation or pivotal movement which is adapted to be operatively connected with a switch or locking bolt in any desirable manner.

As shown in the drawings the hub carries a cam or extension 20 which extends through the hole 13 in the casing and this cam may have screw holes 21 to receive screws for operatively connecting the extension or cam with the operating element of a switch for operating the latter or with a lever for operating a bolt. The hub is rotatably or pivotally mounted in the hole in the casing which hole and cam constitute a bearing means for the hub. Although the hole and rotatable hub are mounted centrally of the circular casing this is not an essential detail of construction but its mounting depends on the size of the casing.

The hub also may carry a sleeve 22 extending outwardly or away from the hub which sleeve is received in the hole 15 in the casing cover 11 and, therefore, the end of the sleeve and the hole

23 in the cover constitute a second bearing means for rotatably or pivotally mounting the hub in the casing. The bearing means also retains the hub in axial position within the casing. The sleeve has a central hole 25 to receive a key K.

Means are provided for rotating the hub by the

key, which means in the construction illustrated, includes the side wall or walls of a slot 23 in the sleeve as well as the side walls of a slot 24 in the hub. It is clear that the side walls formed by either slot constitute key engaged means or key receiving means which is sufficient to rotate the hub by the key.

Any suitable means may be utilized to limit the extent of pivotal movement of the hub. The stop means shown includes a pair of stop pins 27 carried by the casing. Each stop pin is engaged by a stop shoulder carried by the hub. For a $\frac{1}{8}$ turn lock the stop shoulder 28 is located at the dot-dash line shown in Figure 2 or in full line in Figure 3 which, therefore, is a $\frac{1}{8}$ turn lock. For a $\frac{1}{4}$ turn switch or lock, a circular slot or recess is provided in the hub on each side thereof and the end of the slot forms a stop shoulder 29. This hub, therefore, may be used for either a $\frac{1}{8}$ turn or a $\frac{1}{4}$ turn lock or any desired extent of operating movement merely by providing slots of the proper length for the degree or amount of pivotal movement needed or desired.

The hub carries a locking post 32 so that it turns with the hub and moves in an arcuate or circumferential path as will be described more fully hereinafter. The hub also may have centering means of any suitable kind that particularly illustrated including a peaked extension 33 carried by the hub which engages a spring 34 each end of which is anchored or secured to a stop pin 27. The spring will have a peak at the center thereof to restore and hold the hub at central position, or in a position with the key slot in the cover and in the hub and sleeve in alignment. In the construction particularly illustrated with the slot 23 in the hub sleeve and the slot 24 in the hub for the key being a close fit with the key, the latter restores the hub to central position when the key is turned to central or key removal position as determined by the key slot 16 in the casing cover 11 and the spring 34 merely retains the same in this central position.

Each stop pin 27 also serves as a pivot for a set of tumblers or leaves for the lock. There may be one tumbler only in each set; however, the lock is more difficult to open by a person without a key, as the number of tumblers increases. Three tumblers 37, 38, and 39 are shown in each set. Each tumbler carries a hole 40 for receiving the pivot or stop pin. Suitable spring means 41 propels each tumbler radially inwardly towards the sleeve or pivot for the hub, the spring means shown being a spring secured to each leaf such as in a slot therein and bending around into contact with the inner casing wall. Each spring, therefore, propels its respective tumbler or leaf toward the pivotal axis of the hub or particularly towards the sleeve 22 of the hub. Each tumbler has an edge 47 which serves as a cam face; that is, the face of the key engages the end face of each tumbler and upon continued rotation thereof, each tumbler is propelled or pivoted outwardly towards the casing wall. Each tumbler of each set of tumblers also has an arcuate land 42 of a different level from that of the other tumblers in the set which engages its respective corresponding or cooperating level or land 43 on the key K and in this manner determines the position of each leaf or tumbler with respect to the key. The lands 42 need not extend the full length of the movement of the key since the engagement of the locking post 32 in the gate slot retains the respective tumbler in position after the post has once entered the gate. It is clear that

the lock functions perfectly with one set of tumblers only upon one side of the key engaged means in which case the lock is operable in one direction of rotation only of the key and hub; however, for a lock suitable to be opened or unlocked by rotation of the key in either direction, two sets of tumblers are required as shown. The lands of like positioned tumblers of each set are of the same level or height.

With a proper key, each tumbler or leaf is propelled radially outwardly and held in a radial position as determined by the cooperating lands upon each respective tumbler and key so that the gate or gate slot 44 of each tumbler is in alignment with that of each of the other tumblers and also so that all of the gate slots of one tumbler set are in alignment with the path of circular movement of the locking post 32 as shown in Figure 3. Continued rotation of the hub, therefore, is permitted because the locking post enters the aligned gates or gate slots in the tumblers, whereby the hub may be rotated a $\frac{1}{8}$ or $\frac{1}{4}$ turn depending upon the construction of the lock and the extent of movement needed to operate a switch or bolt. If the gate in each tumbler is not in alignment with that of the other tumblers and in alignment with the circular path of movement of the locking post 32, the latter engages the edge face of any such tumbler or tumblers not in such alignment and the hub 19 cannot be turned and consequently the lock remains locked or the switch remains unoperated. Each gate or gate slot is circular upon an arc to correspond with the path of movement of the locking post when the gate is in alignment with the post. Also each gate slot preferably is long enough so that it can be used with either a $\frac{1}{8}$ turn, $\frac{1}{4}$ turn or other degree of movement or turn desired to operate the switch or bolt. One set of tumblers is suitable therefore for the different types of switches. For the greater turn, the locking post rides or moves a greater distance into the gate slot.

If the key to be used were similar on each face thereof, then an identical set of pivoted tumblers or leaves are mounted upon the pivot or stop pin 27 on the left hand side of the casing. However, the key K shown has a recess shown as a slot, undercut or groove 45 therein which alters this operating face of the key and hence the tumblers of the left hand set, although similar, are not identical with the right hand set because the time of operation is different by virtue of the fact that the key is not symmetrical on each face thereof. With the right hand set of tumblers operating from a flat face on the key, each tumbler may be operated simultaneously. With the left hand set of tumblers operating from a face having a groove 45 in the key, some of the tumblers may and particularly the center one 38 with the key shown pivots radially outwardly later than the other tumblers because the key face which operates against the end edge or cam of the tumbler is at the bottom of the transverse groove 45 in the key. For this reason the lower edge face of the tumbler 38 is shorter or farther away from the locking post in central position than other tumblers or leaves so that all tumblers may have time to be moved by the key to a position with their gates in alignment with each other and in alignment with the path of arcuate movement of the locking post irrespective of the delayed operation of any one or more of the tumblers. In other respects the tumblers are the same and similar parts are similarly numbered. Each tumbler may have a

stop shoulder 46 which rides against the sleeve 22 carried by the hub and limits the radial inward movement thereof.

Each tumbler or leaf may have a non-pick finger or extension 49 upon the end thereof. Supposing that someone attempts to pick the lock and make an unauthorized entry. In the first step in picking a lock, the hub and hence the locking post 32 is rotated until stopped by engaging the end of the tumblers, after which each tumbler is moved outwardly until the gate 44 thereof is in alignment with the post. As will be observed in Figure 5, when the hub is rotated without a key or with an improper key, the locking post 32 moves to a position in back of the non-pick extension or finger 49 so that if the tumbler is now pressed outwardly in an attempt to bring the gate 44 in alignment with the locking post, this cannot be done because the extension is engaged by the locking post. Each tumbler preferably carries such a non-pick extension or finger.

It will be noted that the pivot of pivot pins 27 serve three purposes namely as a stop to limit the pivotal movement of the hub, as a pivot pin for its set of tumblers 37, 38 and 39 and as a mounting for the hub centering means or spring 34. This materially simplifies the construction of the lock.

This invention is presented to fill a need for improvements in a lock with pivoted tumblers. It is understood that various modifications in structure, as well as changes in mode of operation, assembly, and manner of use, may and often do occur to those skilled in the art, especially after benefitting from the teachings of an invention. Hence, it will be understood that this disclosure is illustrative of preferred means of embodying the invention in useful form by explaining the construction, operation and advantages thereof.

What is claimed is:

1. A lock adapted to be operated by a key comprising a casing, a hub, means mounting the hub for pivotal movement in the casing, key engaged means carried by the hub adapted to be engaged by the key to turn the hub, a locking post carried by the hub and movable in an arcuate path therewith, at least one tumbler means carried by the casing, each tumbler means including at least one tumbler on one side of the key engaged means and having an end adjacent the key engaged means, pivot means for the tumbler means, the end of each tumbler adjacent the key engaged means providing a cam face, a land on each tumbler facing radially towards the hub pivot means, each tumbler having an arcuate gate which has a width and length to pass the locking post when the tumbler is in key operated position, and spring means urging each tumbler radially inwardly towards the hub pivot means.

2. A lock as in claim 1 including at least one tumbler on the other side of the key engaged means.

3. A lock as in claim 1 including stop means carried by the casing and engaging the hub upon predetermined rotation thereof thereby limiting the pivotal movement of the hub.

4. A lock as in claim 1 in which the hub includes a plate having a key slot the side walls of which form the key engaged means.

5. A lock as in claim 1 including a sleeve secured to the hub having a key slot in the sleeve the walls of which form a part of the key engaged means carried by the hub, a cover plate for the

casing, and bearing means carried by the sleeve and cover plate to rotatably support the hub within the casing.

6. A lock as in claim 5 the hub including a plate having a slot in the plate the walls of which form key engaged means with the walls of the slot in the sleeve.

7. A lock as in claim 1 including a sleeve secured to the hub, a stop shoulder on each tumbler and engaging the sleeve to limit the inward movement of the tumbler.

8. A lock as in claim 1 including means retaining the hub in central position.

9. A lock as in claim 1 in which the hub carries at least one stop shoulder, and the pivot means for the tumbler means is located with respect to the stop shoulder to limit the pivotal movement of the hub.

10. A lock as in claim 1 in which the hub carries at least one stop shoulder, the pivot means for the tumbler means being located with respect to the stop shoulder to limit the movement of the hub, a pointed extension carried by the hub, and spring means anchored to the pivot means for the tumbler means engaging the pointed extension for retaining the hub in central position.

11. A lock as in claim 1 including a non-pick finger upon the end of at least one tumbler forming an obstruction between the locking post and arcuate gate when the post engages the tumbler.

12. A lock as in claim 1 in which the hub carries a stop shoulder adapted to engage the pivot means.

13. A lock as in claim 1 including hub centering means including a part carried by the hub and a part mounted upon the pivot means.

14. A lock as in claim 1 including a stop shoulder carried by the hub and adapted to engage the pivot means and a centering means for the hub including a part carried by the hub and a part mounted upon the pivot means.

15. A lock adapted to be operated by a key having a recess on one face thereof to receive at least one tumbler, comprising a casing, a hub, means mounting the hub for pivotal movement in the casing, key engaged means carried by the hub adapted to be engaged by the key to turn the hub, a locking post carried by the hub and movable in an arcuate path therewith, a pair of tumbler means carried by the casing and one being located upon each side of the key engaged means, each tumbler means including at least one tumbler and having an end adjacent the key engaged means, pivot means for each tumbler means, each tumbler having a cam face on the end thereof adjacent the key engaged means, a land on each tumbler facing radially towards the hub pivot means, each tumbler having an arcuate gate which has a width and length to pass the locking post thereinto when in key operated position, the arcuate gate for a tumbler which engages in a recess in the key having its open end spaced a greater distance with respect to the edge of the land to permit a greater pivotal movement of the hub before the locking post enters the gate, and spring means urging each tumbler radially inwardly towards the hub pivot means.
